UNITED STATES PATENT OFFICE.

HAROLD HERBERT, OF LISCARD, ENGLAND.

SEWING-MACHINE.

1,318,275.

Specification of Letters Patent.

Patented Oct. 7, 1919.

Application filed November 12, 1915. Serial No. 61,191.

To all whom it may concern:

Be it known that I, HAROLD HERBERT, a subject of the King of England, and resident of Liscard, in the county of Chester, England, have invented new and useful Improvements in Sewing-Machines, of which the following is a specification.

This invention has reference to machines for repairing cuts, holes, or the like, in textile fabrics, or for reinforcing or strengthening the same; and more particularly it relates to the class of machine used for this purpose, in which a plurality of needles are employed and arranged, preferably in parallel, and move together, and have threads passed through their eyes; and beneath the table over which the work passes there is employed in connection with the needles chain stitch or the like looper devices.

The object of the present invention is to improve this stitching or work performed on the fabric, and to increase or better distribute the reinforcing or strengthening effect.

The machine according to this invention is constructed and adapted to cause the loops from a row of needles and stitches or work performed by one descent and action of the set of needles, to be so moved by the looper or like device, as to be caught by the loops formed in the next succeeding action of the needles, and locked by the same.

The loops are arranged and adapted to be moved from the different needles diagonally, so that the loop from one outside needle of the set will be moved so as to be caught and locked by the next needle in succession, in the subsequent action of the needles; while the loop of the final needle on the other end of the set is not moved diagonally, but longitudinally or parallel with the stitching, and is caught by the ordinary looping method; while the loop from the needle next it, will also be caught by the looping of this last needle. The work and mechanism of this last needle may be of the ordinary chain stitch type.

The different rows of stitching or work in the fabric operated upon are thus linked up, one in the other, in the transverse or diagonal manner; and therefore the supporting or reinforcing and strengthening of the fabric by the work or stitching, is better distributed, being extended over the surface.

The stitching or looping on the under side

of the work, possesses the knitting principle of interlooping, or its effect.

The invention is illustrated in the annexed drawings in connection with which it will be further described.

In the drawings, Figure 1 is a side elevation; and Fig. 2 a plan illustrating one mode of and mechanism for carrying out the invention; Fig. 3 is a plan showing the throat plate arrangement; and Fig. 4 is a view of the under side of the piece of material showing the form of stitching and work effected by the machine.

Figs. 5 to 7 illustrate a modification.

Referring to the drawings, *a* is the general frame of the machine; *b* are the needle holders of which there are five in the case shown; *c* are the needles; and *d* is the work plate or table. The holders and needles are coupled together and are adapted to be moved simultaneously up and down.

The means by which the loops of all but one of the needles are made and held, in the case shown, consists of a plurality of hooked beaks *e* carried on a sliding plate *f*, and having movement obliquely to the vertical plane in which the needles stand and move; while the loop of the remaining needle is made by the looping device *g* carried on a lever *g¹* hinged at *g²*.

The slide *f* carrying the loopers *e*, works in a guide *f¹* and is operated by a reciprocating bar *h* from the driving gear of the machine through a connecting rod *i*.

The looper *g* in the case shown is also adapted to be oscillated about its pivot by part of the rod or slide *h*.

The work support *d* is formed with a throat aperture *k*, having one longitudinal edge, that is the edge nearest the path of the needles, formed with projections between which the needles pass in the sewing operation. The opposite edge is straight. A second plate overlies and is secured to the work plate, such second plate having resilient tongues *l* which overlie and rest with slight spring pressure on the work support *d*, extending beyond the straight edge of the throat aperture *k*. The free ends of these tongues extend in the direction of feed of the fabric.

As the needles project through the fabric and below the same and ascend a loop of thread is formed, which loop is picked up by the appropriate looper, and moved laterally with respect to the needles to a position in

the path of movement of the next needle. The needles rise clear of the fabric, which latter is then moved by the usual feed. The loopers hold the end of the loops in the path 5 of the adjacent needles, the feed of the fabric carrying the fabric connected end of the loop forward, thus arranging the loop diagonal. The next adjacent needle in its next descent passes through the fabric, between one side 10 of the previously formed loop moved by the looper beneath such needle, (the looper being still in position) and the looper, and the looper is then withdrawn leaving the loop end on the needle.

15 The final looper *g* however, instead of moving to position its loop beneath the next adjacent needle, is operated to carry its loop into the succeeding path of the same needle which forms the loop. This interlocks the final loops and so interlocks all 20 the loops, as will be plain from Fig. 4.

Fig. 4 shows the form of the work or stitching performed and how the loops are moved obliquely, so that the thread from one 25 needle is moved into the position that the outer end of each loop will stand in the position coincident with that of the next needle in sequence, and will in the next stroke be caught by this needle in this stroke; and it 30 also shows the looping of the last needle in series, which is an ordinary chain stitch looping; this last needle passing through the loop of its own thread made in the last descent of the needle, and also through the loop 35 from the needle next it; and this last needle and its loops hold the end loops of the chain loopings of the series of loops performed by the other needles of the set.

In the modification shown in Figs. 5 to 7 40 the needle bars and needles *b*, *c* are shown obliquely arranged to the direction of feed of the fabric, in which case the loops will move at right angles to such line of feed, the final looper moving in the direction of the 45 line of feed.

The stitching resulting from this form is shown in Fig. 7, the main loops being in the line of fabric feed and the final loops being at right angles thereto.

50 In either form all loops are interfitted one with another, and the final loops which hold the full series of any one operation of the needles are interlocked one with another.

The loops are formed around, that is beneath the projections of the comb-like edge 55 of the throat aperture *k* of the work support

d, and as these loops are gradually moved under the feed of the fabric, the spring tongues *l* act to exert sufficient pressure thereon to prevent distortion of the loops on 60 an undue strain thereon where connected to the fabric, during the pull on such loops by the loopers. The loops of course ride beneath these fingers and between them and the work plate *d*, finally riding free of such 65 fingers at the free ends thereof.

What is claimed is:—

1. In a sewing machine, the combination of a plurality of alined needles, a plurality of alined loopers, means for moving the 70 loopers at an angle to the path of movement of the needles to engage the loops of such needles below the fabric and to carry such loops into the path of the next adjacent needle; whereby to permit such adjacent 75 needle to pass through such positioned loop, and an additional looper to coöperate with the loop of the final needle, and means for moving such additional looper to move the loop of such final needle into a position to 80 be engaged by the final needle in its next movement through the fabric, whereby the loops of needles other than the final needle are interengaging and the loops of the final needle interlocked one with another to se- 85 cure all loops.

2. In a sewing machine, a plurality of alined needles, a plurality of loopers arranged to move at an angle to the path of movement of certain of the needles, means to 90 operate the loopers to carry the loops of the respective needles into the path of movement of the next adjacent needle, an additional looper for the final needle, one of the first mentioned loopers carrying the loop of 95 the needle next to the final needle into the path of and so as to be engaged by such final needle, and means for operating such additional looper to carry the loop of the final needle at an angle to the loop of the other 100 needles and into the next succeeding path of movement of the final needle, whereby the loops of the final needle are interengaged with the loops of adjacent needles and with each other.

105 In testimony whereof I have signed my name to this specification in the presence of two subscribing witnesses.

HAROLD HERBERT.
